CONTROL FOR STOPPING LOOMS

Joseph M. Godreau, Moosup, Conn.

Application November 21, 1946, Serial No. 711,389

8 Claims. (Cl. 139—377)

1

This invention relates to a loom and more particularly to a control for stopping the loom. It is usual in the operation of a loom which is automatically caused to stop when the filling fails that the shuttle will come to rest at the transfer end of the lay rather than at the end of the lay where the shipper lever with its handle is located. When the shuttle of a loom comes to rest at the end of the lay remote from that end at which the shipper handle is located, it becomes necessary for the loom operator to turn over the crank shaft by hand and move the shuttle from the transfer end of the lay to the shipper handle end of the lay to piece up the filling. A loom operator who does turn over the crank shaft for this purpose usually gets his hands dirty and the woven fabric or thread will in many instances thus become soiled from the operator's hands, besides some time is consumed in the turning over the loom for such piecing up.

One of the objects of this invention is to so delay the movement of the shipper handle in its travel from operating position to inoperating position that the shuttle will take one more pick and will come to rest at the shipper handle end of the lay.

Another object of this invention is to provide a very simple attachment to the already-existing loom which may be simply assembled thereon to cause the desired action.

A more specific object of this invention is to provide a hook which will catch the shipper handle when released from its operating position to retain the shipper handle until the filling motion has returned from a position which causes release of the shipper handle.

With these and other objects in view, the invention consists of certain novel features of construction as will be more fully described and particularly pointed out in the appended claims.

In the accompanying drawings:

Fig. 1 is a top plan view with the shipper lever and other parts in section showing a fragmental portion of a loom with my invention in position.

Fig. 2 is a view similar to Fig. 1 of a lesser portion of the loom and showing the shipper lever as initially moved from its operating position and caught by the catch which is a feature of this invention.

Fig. 3 is a sectional view through the filling motion prior to engagement with the lever which moves the shipper lever.

Fig. 4 is a sectional view showing the shipper lever and spring for moving it to one end of the slot in which it operates.

2

In proceeding with this invention, I attach a catch on the release or shipper motion lever which pushes the shipper handle or lever from its operating position into a position to stop the loom, which catch will engage the shipper lever and hold it from moving to inoperative position, and I also provide a spring which, after the filling fork slide has returned from actuating position, will cause the release lever to release the shipper lever by retracting the hook from engagement therewith. This retarding of the stopping of the loom will be so timed as to cause the shuttle to move to the shipper handle end of the lay, making it unnecessary to turn over the crank shaft by hand and manually move the shuttle across the lay.

With reference to the drawings, 10 designates a part of the framework of the loom and 11 the cam shaft having a cam 14 thereon which engages 20 the cam follower 15 secured at the end of the cam follower lever 16 which is pivoted as at 17 (see Fig. 3) and has a follower dog 18 secured on the other side of its pivot which oscillates each time the cam shaft rotates. This dog has the cam follower trip 19 secured thereon as well as a filling motion hook 20. The filling fork 21 is mounted in its holder 22 and pivoted as at 23 and has a latch 24 to engage the catch 25 of the filling motion hook 20 in case the filling 26, which is shown as spaced from the lay (Fig. 1) designated generally 27, fails or is not present to swing the trip 21 out of the way. The filling fork slide designated generally 27 has mounted on it the filling motion trip 28, and this slide will move forwardly on the filling motion stand 29 so that the trip 28 will engage the filling motion finger 30 on the end of the shipper motion lever 31, which is pivoted as at 38, to swing the arm 39 of the release lever 37 into engagement with the shipper lever 40 having a handle 35 at the upper end thereof (see Fig. 4).

This shipper lever is shown as located in the slot 41 in the shipper lock 42 which has an offset or notch 43 along one wall 44 of the slot 41 so as to provide a shoulder 45 with which the shipper lever 40 engages to be locked against the action of a spring indicated at 36 (see Fig. 4) which tends to move the shipper lever to the inoperative end 46 of the slot 41. A spring 47 is anchored in the arm 48 which is fixed relative to the lever 37 and extends about one arm of release lever 37 tending to swing the lever counter-clockwise about the pivot 38 as shown in Figs. 1 and 2.

55 A hook 50 is mounted on the arm 39 of release

lever 37 which contacts the shipper lever 40. This hook is provided with an abutment surface 51 to engage the edge 52 of the shipper lever 40 and hold the same while in engagement therewith. This surface 51 is so positioned on the arm 39 that, when the shipper lever is in operating position, the surface will be spaced from the shoulder 45 in the direction of the inoperative end 46 of the slot 41.

When the conditions are such that the lever 37 will be swung clockwise around its pivot 38 by movement of the filling fork slide, the end of the arm 39 will push the shipper lever out of the notch 43 and beyond the shoulder 45. The shipper lever will then start to move toward the inoperative end 46 of the slot 41 by a constantly acting tension spring 36 usual in mechanisms of this character with the shipper lever sliding along the wall 44 of the slot. However, before the shipper lever has moved any substantial amount, the surface 51 of the catch 50 will engage the shipper lever and arrest its movement. Thus, the shipper lever does not move far enough to cause stopping of the loom, and the shuttle 55 which has travelled to the transfer end of the loom will be returned by the picker stick at the transfer end of the loom into the shuttle box 56 as shown in Fig. 1. However, the spring 57, as shown in Figs. 1 and 2, is acting upon the filling fork slide to return the slide; and after the slide is returned, the spring 47, acting upon the releasing lever 37, will swing this lever counter-clockwise to withdraw the catch or hook 50 from the shipper lever 40, which being against the wall 44, as shown in Fig. 2, is then free to be moved by its spring 36 along the wall 44 to the inoperative end 46 of the slot 41 and the loom will be stopped.

By this arrangement, the delay in the movement of the shipper handle to an inoperative position by catching the same and holding the same until the filling fork slide has returned permits just sufficient time for the picker stick at the opposite end of the loom to operate and cause the shuttle to be returned to the end of the loom where the shipper lever is located.

It will be apparent that the shipper lever is provided with the usual handle for operation which extends upwardly and is enlarged somewhat from the lever portion 40 thereof which is cut off in the showing in the drawing so as not to hide the edge of the lever which catches on the abutment 45 and the action with hook 50 which would otherwise be hidden.

I claim:

1. In a loom, a shipper lever, a spring to move the lever in one direction, a shipper lock comprising, a body having a slot in which said lever is movable with an offset notch to receive said lever and providing a shoulder to engage said lever to lock the lever in operating position against the action of said spring, means to move said lever out of said notch upon failure of the filling and means to catch the shipper lever when moved from said shoulder and delay its movement by said spring.

2. In a loom, a shipper lever, a spring to move the lever in one direction, a shipper lock comprising, a body having a slot in which said lever is movable with an offset notch to receive said lever and providing a shoulder to engage said lever to lock the lever in operating position against the action of said spring, a release lever responsive to the failure of the filling to move said shipper lever out of said notch and means carried by said

release lever to catch the said shipper lever and delay it from being moved by said spring to stop the loom.

3. In a loom, a shipper lever, a spring to move the lever in one direction, a shipper lock comprising, a body having a slot in which said lever is movable with an offset notch to receive said lever and providing a shoulder to engage said lever to lock the lever in operating position against the action of said spring, a release lever responsive to the failure of the filling to move said shipper lever out of said notch and means carried by said release lever to catch said shipper lever and delay it from being moved by said spring to stop the loom, said means catching said shipper lever after leaving said shoulder and holding it along the edge of the wall of said slot.

4. In a loom, a shipper lever, a spring to move the lever in one direction, a shipper lock comprising, a body having a slot in which said lever is movable with an offset notch to receive said lever and providing a shoulder to engage said lever to lock the lever in operating position against the action of said spring, means to move said lever out of said notch upon failure of the filling and a hook to catch the lever when moved from said shoulder and delay its movement by said spring until said lever moving means moves said lever from said hook.

5. In a loom, a shipper lever, a spring to move the lever in one direction, a shipper lock comprising, a body having a slot in which said lever is movable with an offset notch to receive said lever and providing a shoulder to engage said lever to lock the lever in operating position against the action of said spring, a release lever responsive to the failure of the filling to move said shipper lever out of said notch and a hook carried by said release lever to catch said shipper lever and delay its movement by said spring to stop the loom.

6. In a loom, a shipper lever, a spring to move the lever in one direction, a shipper lock comprising, a body having a slot in which said lever is movable with an offset notch to receive said lever and providing a shoulder to engage said lever to lock the lever in operating position against the action of said spring, a release lever responsive to the failure of the filling to move said shipper lever out of said notch and a hook carried by said release lever with its engaging surface parallel to said shoulder but spaced toward the inoperative shipper lever position from said shoulder to catch said shipper lever while engaging the side of the slot and delay its movement by said spring to stop the loom.

7. In a loom, a shipper lever, a spring to move the shipper lever in one direction, a shipper lock comprising, a body having a slot in which said lever is movable with an offset notch to receive said lever and providing a shoulder to engage said lever to lock the lever in operating position against the action of said spring, a release lever responsive to the failure of the filling to move said shipper lever out of said notch and a hook carried by said release lever with its engaging surface parallel to said shoulder but spaced toward the inoperative handle position from said shoulder to catch said shipper lever while engaging the side of the slot and delay its movement by said spring to stop the loom until a subsequent movement of said release lever.

8. In a loom, a shipper lever, a spring to move the lever in one direction, a shipper lock com-

prising, a body having a slot in which said lever is movable with an offset notch to receive said lever and providing a shoulder to engage said lever to lock the lever in operating position against the action of said spring, a release lever responsive to the failure of the filling to move said shipper lever out of said notch and a hook carried by said release lever with its engaging surface parallel to said shoulder but spaced toward the inoperative shipper lever position from said shoulder to catch said shipper lever while engaging the side of the slot and delay its movement by said spring to stop the loom until

5 a subsequent return movement of said release lever.
